CLAIM

The ornamental design for a motor, as shown and described.

DESCRIPTION

FIG. 1 is a back view of the motor according to a first embodiment of the invention.

FIG. 2 is a bottom view of the motor according to a first embodiment of the invention.

FIG. 3 is a front view of the motor according to a first embodiment of the invention.

FIG. 4 is a left side view of the motor according to a first embodiment the invention.

FIG. 5 is a perspective view of the motor according to a first embodiment the invention.

FIG. 6 is a right side view of the motor according to a first embodiment the invention.

FIG. 7 is a top view of the motor according to a first embodiment the invention.

FIG. 8 is a back view of the motor according to a second embodiment of the invention.

FIG. 9 is a bottom view of the motor according to a second embodiment of the invention.

FIG. 10 is a front view of the motor according to a second embodiment of the invention.

FIG. 11 is a left side view of the motor according to a second embodiment the invention.

FIG. 12 is a perspective view of the motor according to a second embodiment the invention.

FIG. 13 is a right side view of the motor according to a second embodiment the invention; and,

FIG. 14 is a top view of the motor according to a second embodiment the invention.

The portions of the article shown in broken lines form no part of the claimed design.

1 Claim, 14 Drawing Sheets
